Inventor:
Samuel Elfman,
by William F. Modern, Atty.

UNITED STATES PATENT OFFICE

SAMUEL ELFMAN, OF BOSTON, MASSACHUSETTS.

MEANS FOR SECURING SHOE HEELS.

Application filed June 11, 1921. Serial No. 476,923.

To all whom it may concern:

Be it known that I, SAMUEL ELFMAN, a citizen of the United States, residing at 17 North Russell Street, city of Boston, county 5 of Suffolk, in the Commonwealth of Massachusetts, have invented a new Means for Securing Shoe Heels, of which the following description, in connection with the accompanying drawing, is a specification, like 10 characters on the drawing representing the parts.

While my invention may be used generally in fastening heels to shoes, it is particularly adapted for use in connection with the high 15 heels on women's shoes.

In the drawing of one embodiment of my invention selected for illustration and description herein,

Fig. 1 is a side elevation of a shoe partly 20 broken away with my novel heel locking member thereon;

Fig. 2, a bottom face view of the device on the heel seat of a shoe and ready to receive the heel;

Fig. 3, a top face view of the device; and

Fig. 4, an end view thereof with a heel partly broken away in position to be seated therein.

Referring first to Figs. 2 and 3, my novel 30 locking member is shown as a flat strip 1, with an inturned edge or flange 2 of suitable width and forming between the strip and flange a channel 3 of convenient width.

The strip may be fashioned of any desired 35 material as aluminum to the outline of the top of the heel seat 4 of the shoe, and fastened thereto by tacks or other suitable members 5.

The heel edge 6, Fig. 3, is then sprung 40 within and beneath the flange 2 and secured therein by pressing the flange 2 closely against the heel edge by means of a screw driver or any suitable tool. While the strip 1 as described, will firmly lock the heel to 45 the shoe, it may, if desired, be still further secured by nails or tacks 7, Fig. 1, dotted lines, driven downwardly through the heel seat into the heel.

It is well known by those familiar with 50 the art that the fastening of the high heels now so much in vogue for women's shoes,

presents perhaps the most difficult problem in the shoe making art.

At the present time the heel is secured to the heel seat by glue and tacks as at 7, Fig. 55 1. After it is glued, it must be clamped to the shoe for several hours for the glue to harden. There are very serious objections to this method. The glue almost invariably gives way at an early date in well made 60 shoes, and at once in cheap shoes, and necessitates expensive repairs.

It takes from ten to twelve hours actual 65 time, and that means a working day, for the glue to dry, thus retarding seriously the output of the factory. The tacks 7 must be driven into the heel over the shank in order to avoid splitting the heel, which would occur if the tacks were driven near the back edge of the heel.

Again, in the cheaper shoes the heel seat 70 is made of such poor material that it gives way readily so that the tacks therethrough do not hold.

In using my improved device, the edge 8 75 of the heel seat 4 is trimmed back somewhat from the edge of the counter or side of the shoe so that the strip 1 may lie close to the heel seat and overlie a little of the edge of the same. It is firmly held in place by the 80 tacks 5 and a new heel may at any time be substituted for the old one by lifting the flange 2 sufficiently to release the old heel and insert the new.

The edge of the strip 1 on the shoe offers 85 an attractive novel feature in appearance and will not tarnish if made of aluminum or some other materials, although it may, of course, be enameled any color if desired. While the locking device will preferably be 90 made in different sizes, the strip 1 may be sprung somewhat laterally very easily and thus one size of the locking device may be used in heel seats varying somewhat in size.

My invention is not limited in all details 95 to the precise embodiment described and illustrated herein, but may be varied within the spirit of the invention and scope of the appended claims.

1. A locking member for securing a de- 100 tachable heel to the heel seat of a shoe sole, comprising a flexible metal strip adapted to

be secured around the edge of the heel seat, and a downwardly extended flange thereon, adapted to engage the outer side edge of the heel and to be bent inwardly against the same to lock it to the shoe leaving the outer shoe sole uninterrupted in length.

2. A heel locking member comprising a heel shaped strip flexible edgewise to the desired size, and adapted to be countersunk in the heel seat of the sole, and secured to and

about the outer edge of the heel seat of the shoe, the strip having a raised flange to receive the heel top edge and constructed and arranged to be turned down against and about the outer edge of the heel to secure the same to the strip and heel seat of the sole, leaving the heel seat of the outer sole uninterrupted in length.

SAMUEL ELFMAN.
